FLEXIBLE POCKET RECEPACLE

Warner R. Buxton, Longmeadow, Mass.

Application July 15, 1931, Serial No. 550,958

11 Claims. (Cl. 150—38)

This invention relates to an improved flexible pocket receptacle, intended primarily for carrying bills, notes, checks and the like and commonly known as a bill fold.

5 An object of the invention is to provide an improved and simple bill fold construction, which embodies novel means for enabling the desirable relative longitudinal shifting movement between the outer and inner walls for the purpose of 10 avoiding buckling of the inner walls when the bill fold, while well filled with bills, is moved to closed position.

Another object of the invention is to provide a one piece construction for a bill fold, having 15 simply outer and inner walls and connecting end flaps, which are so located and arranged as to enable a considerable and sufficient degree of shifting of the free or upper edge of the inner wall relative to the outer wall.

20 Preferably, the connection between each end flap and the inner wall is a single one, located near the lower edge of the inner wall,—such edge being the edge that is attached to the outer wall. Then the inner wall is transversely 25 slotted in that part which overlies the central transverse line of fold in the outer wall,—the slot extending from the lower edge of the inner wall upwardly toward, but not to, the upper edge of the inner wall. With this arrangement, the 30 upper portion only of the inner wall needs to shift relatively to the outer wall when the bill fold is opened or closed, and such shifting is permitted because of the low location of the connection between the end flap and the inner wall 35 and because of the use of a single connection which enables a limited degree of relative swinging or pivotal movement between the connected parts.

Other features of the invention will appear as 40 the detailed description proceeds and will be pointed out in the appended claims.

The invention will be disclosed for illustrative purposes with reference to the accompanying drawing, in which:—

45 Fig. 1 is a developed view of the blank from which the bill fold is made;

Figs. 2 and 3 are elevational views of the bill fold, showing the same in open and closed positions, respectively;

50 Figs. 4 and 5 are full size plan views of the bill fold, showing the same in open and closed positions, respectively;

Fig. 6 is a cross sectional view taken on the line 6—6 of Fig. 2; and

55 Fig. 7 is a full sized elevational view showing

the bill fold partially closed and illustrating the manner in which the inner wall shifts to avoid buckling.

Referring to the drawing, the bill fold may to advantage be made from a single piece of suitable 60 flexible material, such as leather or the like, and where the one piece construction is desired, a blank of leather or other material is cut out in the form shown in Fig. 1. This blank affords an outer wall 8 of rectangular form; an inner 65 wall 9 integrally and foldably connected along one side edge to the lower side edge of the outer wall; and two end flaps 10, which are integrally and foldably connected one to each end edge of the outer wall. The lines of intersection between 70 parts 8 and 9 and between parts 8 and 10 are preferably scored, as at 11 and 12, respectively. The outer wall has a transverse line of fold 13, preferably scored to facilitate bending, and the inner wall has a similar but much shorter line 75 of fold 14. Most of the central portion of the inner wall is cut away by a slot 15 which extends transversely from the line of fold 11 or lower side edge of the inner wall toward, but not to, the free and upper side edge of such wall. The end 80 flaps 10 have tongues 16 to engage in and interlock with slots 17 formed in the inner wall when the latter is superposed on the outer wall.

The bill fold is formed from the described blank in a very simple manner. The inner wall 9 is 85 folded along line 11 and swung upwardly over and upon the outer wall 8 into superposed relation therewith. The end flaps 10 are then folded inwardly along lines 12 and swung over and upon the inner wall 9 in overlapping relation with the 90 end portions thereof. The parts are then held together in folded relation by inserting the tongues 16 in slots 17. The bill fold then appears as in Figs. 2 and 4, the space between the walls 8 and 9 forming a compartment for bills *b* and 95 the like. To close the bill fold, one half is folded about lines 13 and 14 over and upon the other half. The parts then appear as in Figs. 3 and 5.

As a desirable refinement, a thin strip of leather 100 18 or other suitable facing material is applied as a lining to the inner face of the inner wall. It may, for example, be fastened in place with adhesive. Its purpose is to cover the projecting tongues 16 and prevent them from interfering with the insertion of bills into the bill compartment. 105

The end flaps, it will be noted, have only a single connection with the inner wall and this is located at a low point on the inner wall. The 110 upper portions of the inner wall are, to a con-

siderable extent, unrestrained by any connection with the outer wall. As a consequence, the upper part of the inner wall can, and does in actual operation, shift longitudinally while the lower parts, being connected to the outer wall along line 11 and by the connection 16, 17, cannot shift longitudinally. The action isn't an exact straight line shift for the inner wall is held at the connection 16, 17 and in shifting, is forced to turn 10 around this connection as a pivot but the degree of shifting required is small enough so that the curvature of the path of movement of the inner wall is inconsiderable and, for all practical purposes, the movement may be considered as in a longitudinal direction.

Without anything more than the ordinary degree of play between the parts 16 and 17, the described action can take place and it could equally well take place if the flap 10 and wall 9 were riveted together at the location of the connection 16, 17. This can best be understood by considering what happens when the bill fold is closed. The inner wall has to bend about a much shorter radius than the outer wall (see Fig. 5). 20 As a consequence, its ends have to move out in opposite directions from the line of fold 13 relatively to the outer wall. This, of course, applies only to the upper portion of the inner wall because the lower portions are slotted as at 15, and do not have to bend but move with the outer wall. As the upper edge of wall 9 is pushed toward an end of the bill fold, it is held at the location 16, 17 and forced to swing around this connection as a pivot. The outer part of wall 9 is 25 forced down and the inner part is forced up, as will be clear from Fig. 7. The lower edge of the inner wall draws up near the slot 15 to enable the outer part to move down. As the lower edge of the inner wall rolls up, as shown at 19, the first action is to take up any play between the wall of slot 17 and the edge 20 of flap 10. If the rolling up of the lower part of the inner wall is continued, the wall of slot 17 will engage edge 20 and swing the end flap upwardly, and the flap being 30 of flexible material, will yield to permit this action. The edge 21, when viewed in plan, will bend outwardly away from the inner wall between its upper and lower ends when the flap thus yields. This bending of flap 10 does not always occur and is not necessary except when an unusually large number of bills *b* are present in the bill compartment. It is, however, pointed out that the flap is free to yield if and when required.

35 The action will also vary somewhat according to the extent of play between the tongue 16 and slot 17. The dimensions *x* and *y* (Fig. 1) may be varied. The dimension *x* is necessarily at least slightly less than the length of slot 17 and it may be made materially less to enable an appreciable degree of sliding of the tongue lengthwise in the slot. So also, the dimension *y* is necessarily at least slightly greater than the thickness of the leather wall 9 and it may be made even greater to permit a substantial degree of upward movement of the wall 9 without engaging edge 20 and moving flap 10. These dimensions *x* and *y* relative to the corresponding dimensions of slot 17 will be a matter of choice. The shifting action is essentially the same regardless of the play in the connection 16, 17 and the presence of play at this point simply has the effect of enabling the shifting of wall 9 to take place without bending flap 9. Some play

is desirable even though it is not essential to the accomplishment of the result.

I have obtained the best results by making the end flaps 10 of roughly triangular form, as shown. Assuming that the line 12 is the base of the triangle and the apex is the intersection of the edges 20 and 21, this apex should be nearer to the lower edge than to the upper edge of the inner wall and the tongue 16 is desirably formed on the lower edge 20. With such an arrangement, the flaps serve effectively as end closures for the bill fold notwithstanding that they each have but one connection with the inner wall. And by the use of such single connection, located nearer to the lower edge than to the upper edge of the inner wall and nearer to the end edge 12 than to the line of fold 13, the wall 9 is afforded freedom to swing, as described, about the single connection 16, 17 to enable the relative longitudinal shifting effect between the inner and outer walls.

95 I believe that I am the first to provide for relative movement between the inner and outer walls of a bill fold in the particular manner herein set forth and I desire to claim my invention in the broadest possible legal manner.

What I claim is:

1. A bill fold, comprising, an outer wall, another wall superposed on the outer wall and connected along one side edge directly to a side edge of the outer wall, and an end flap connected to one end edge of one of said walls and overlapping an end portion of the other wall, said flap having a connection with such portion of the other wall near said side edge, said connection enabling a limited degree of pivotal movement between the flap and the wall to which it is connected and constituting the only connection between said flap and last named wall.

105 2. A bill fold, comprising, an outer wall, an inner wall connected along one side edge directly to a side edge of the outer wall, substantially triangular end flaps having their base edges connected one to each end edge of the outer wall and overlapping the end parts of the inner wall the other two edges of each said flap extending substantially from the two adjacent corners of the outer wall at acute angles to the base edge of the flap until they intersect, and a single connection only between each triangular end flap and the inner wall located close to the point of intersection of said other two edges of the flap.

115 3. A bill fold, comprising, an outer wall, an inner wall connected along one side edge directly to a side edge of the outer wall, substantially triangular end flaps having their base edges connected one to each end edge of the outer wall and overlapping the end parts of the inner wall the other two edges of each flap extending substantially from the two adjacent corners of the outer wall at acute angles to the base edge of the flap until they intersect, and a single connection only between each triangular end flap and the inner wall at a location close to the point of intersection of said other two edges, said connection comprising a tongue on that one of the last named two edges which lies nearest to said side edge and a slot in the underlying part of said inner wall, said slot paralleling the edge 120 having the tongue.

125 4. In a bill fold, an outer wall, an inner wall connected along one side edge directly to a side edge of the outer wall, and substantially triangular end flaps overlapping the inner wall one 130

near each end thereof, one edge of each triangular flap being connected to the adjacent end edge of the outer wall and a free portion of said flap near its apex having a tongue and slot connection with the inner wall, the slot of said connection disposed at an acute angle to said side edge and nearer to such side edge than to the opposite side edge of the outer wall.

5. In a bill fold, an outer wall having intermediate its ends a transverse line of fold, an inner wall superposed on the outer wall and connected thereto along its lower edge, said inner wall having a transverse slot extending from its lower edge toward but not to the upper edge and overlying said line of fold, and means connecting each end edge of the outer wall to the inner wall at a point near the lower edge of the inner wall leaving its upper ends unattached and free for a limited degree of longitudinal shifting movement.

6. In a bill fold, an outer wall having intermediate its ends a transverse line of fold, an inner wall superposed on the outer wall and connected directly thereto along its lower edge, said inner wall having a transverse slot extending from its lower edge toward but not to the upper edge and overlying said line of fold, and end flaps connected one to each end edge of the outer wall and each having a single connection only with the inner wall enabling a limited degree of pivotal movement between the inner wall and each flap.

7. In a bill fold, an outer wall having intermediate its ends a transverse line of fold, an inner wall superposed on the outer wall and connected directly thereto along its lower edge, said inner wall having a transverse slot extending from its lower edge toward but not to the upper edge and overlying said line of fold, substantially triangular end flaps connected along one edge one to each end edge of the outer wall and overlapping the end portions of the inner wall, and a tongue and slot connection between each end flap and the inner wall located near the apex of the triangular flap, said connection constituting the only connection between the flap and inner wall.

8. In a bill fold, an outer wall having intermediate its ends a transverse line of fold, an inner wall superposed on the outer wall and connected thereto along its lower edge, said inner wall having a transverse slot extending from its lower edge toward but not to the upper edge

and overlying said line of fold, substantially triangular end flaps connected along one edge one to each end edge of the outer wall and overlapping the end portions of the inner wall, and a tongue and slot connection between each end flap and the inner wall located near the apex of the triangular flap and closer to the lower edge of the inner wall than to its upper edge.

9. In a bill fold, an outer wall having intermediate its ends a transverse line of fold, an inner wall superposed on the outer wall and connected thereto along its lower edge, said inner wall having a transverse slot extending from its lower edge toward but not to the upper edge and overlying said line of fold, and end flaps connected one to each end edge of the outer wall, said flaps being approximately triangular in shape with their upper free edges directed approximately from the upper corners diagonally toward the lower extremity of said line of fold and their lower free edges directed from the lower corners at a lesser degree of slope toward and to said upper free edges, and a single connection between each flap and inner wall at a point near the intersection of said free edges.

10. In a bill fold, an outer wall having intermediate its ends a transverse line of fold, an inner wall superposed on the outer wall and connected thereto along its lower edge, said inner wall having a transverse slot extending from its lower edge toward but not to the upper edge and overlying said line of fold, and end flaps connected one to each end edge of the outer wall, said flaps being approximately triangular in shape with their upper free edges directed approximately from the upper corners diagonally toward the lower corners and their lower free edges directed from the lower corners at a lesser degree of slope toward and to said upper free edges, and a tongue and slot connection between each said lower free edge and the inner wall enabling limited relative movement therebetween.

11. A bill fold, comprising, an outer wall, an inner wall connected along one side edge directly to a side edge of the outer wall, end flaps connected one to each end edge of the outer wall and overlapping the end parts of the inner wall, and a single connection only between each end flap and the inner wall enabling limited pivotal movement between the inner wall and each flap about an axis located adjacent the end of said side edge adjacent said flap.
